(57) **CLAIM**

The ornamental design for a leak detection soil dipole probe, as shown and described.

DESCRIPTION

FIG. 1 is a perspective view of a leak detection soil dipole probe, showing my new design in an expanded configuration;

FIG. 2 is a front elevational view of FIG. 1, the rear elevational view being a mirror image thereof;

FIG. 3 is a left-side elevational view of FIG. 1;

FIG. 4 is a right-side elevational view of FIG. 1;

FIG. 5 is a top plan view of FIG. 1;

FIG. 6 is a bottom plan view of FIG. 1;

FIG. 7 is a perspective view thereof, illustrated in a collapsed configuration;

FIG. 8 is a front elevational view of FIG. 7, the rear elevational view being a mirror image thereof;

FIG. 9 is a left-side elevational view of FIG. 7;

FIG. 10 is a right-side elevational view of FIG. 7;

FIG. 11 is a top plan view of FIG. 7; and,

FIG. 12 is a bottom plan view of FIG. 7.

The broken lines showing a power cable in the figures depict portions of the leak detecting soil dipole probe that form no part of the claimed design.
